UNITED STATES PATENT OFFICE

170,086

TELEPHONE SHOULDER REST

Sydney E. Harmon, Evanston, Ill.

Application January 29, 1953, Serial No. 23,341

Term of patent 14 years

(Cl. D26—14)

To all whom it may concern:

Be it known that I, Sydney E. Harmon, a citizen of the United States, and resident of Evanston, Cook County, Illinois, have invented a new, original, and ornamental Design for a Telephone Shoulder Rest, of which the following is a specification, reference being had to the accompanying drawing, forming a part hereof.

Fig. 1 is a plan view of my new telephone shoulder rest.

Fig. 2 is an edge view of Fig. 1.

Fig. 3 is a perspective view of the telephone shoulder rest, showing my new design.

I claim:

The ornamental design for a telephone shoulder rest, as shown.

SYDNEY E. HARMON.
